Switzerland, assignors to Knorr-Nährmittel
Aktiengesellschaft, Thayngen, Switzerland

Application October 16, 1939, Serial No. 299,756
In Switzerland October 29, 1938

12 Claims. (Cl. 226—57)

This invention relates to a method of and means for making knots of string, thread, wire or the like, which serve to tie up articles, and more particularly the invention relates to the automatic formation of knots adapted to tie up the ends of wrapped articles having the shape of sausages, or to close bags and the like. Heretofore such knots have mostly been tied by hand, and the primary object of the invention is to replace the manual tying of such knots by the provision of an improved method of and a machine for mechanically tying knots adapted for the above mentioned use.

The method according to the invention consists in winding a piece of knot material, such as string, thread or wire, on a winding member in at least two relatively staggered and superposed windings in loose shape, stripping this loose knot off the winding member and pushing it upon the article to be tied, and then pulling the knot tight.

The machine for making the knot according to the invention comprises a winding device having a rotatable winding member arranged for axial movement and provided with means for clamping a piece of knot material thereto, means for imparting at least two revolutions to the winding member in order to place the knot material in at least two windings about the same, means for axially moving the winding member to-and-fro during its movements of rotation, and a stripping member for stripping the wound knot from the winding member and sliding it upon the article.

The piece of knot material may be folded in two halves before its clamping to the winding member so as to present a loop at one of its ends by means of which the article, after the knot has been pulled tight, can be suspended.

The invention will now be described with reference to the accompanying drawings illustrating a preferred embodiment of a knot tying machine and a modification thereof.

Figure 1 is a view in elevation of a knot tying machine according to the invention.

Figure 2 is a section according to the line II—II of Fig. 1.

Figure 3 is a section according to the line III—III of Fig. 2.

Figure 4 is a section according to the line IV—IV of Fig. 3.

Figure 5 is a section according to the line V—V of Fig. 2.

Figure 6 is a section according to the line VI—VI of Fig. 2.

Figure 7 is a partial plan view of the string feeding device.

Figure 8 is a section according to the line VIII—VIII of Figure 2, showing the mechanism for imparting rotation to the knot winding member.

Figure 9 is an axial section through the winding member.

Figure 10 is a perspective view of the front end of the winding member showing the manner of feeding the string destined to form a knot.

Figure 11 is a perspective view showing a piece of string wound around the front end of the winding member.

Figure 12 is a vertical section through the front end of the winding member showing the two ends of the string ready to be gripped by the knot tightening members.

Figure 13 shows the loose knot placed upon the article to be tied.

Figure 14 shows the finished knot.

Figure 15 shows a modified arrangement of a knot tying machine according to the invention.

Referring to the drawings, the represented knot tying machine comprises a base plate 1 carrying a vertical frame member 2 and spaced therefrom a vertical frame plate 117 (Figs. 1 and 2). A horizontally extending L-shaped frame member 3, 3a is disposed between the member 2 and plate 117; the branch 3 of this L-shaped member is secured to the plate 117 intermediate its height, while the branch 3a, bent over at right angles, is united with the top of the vertical frame member 2. The branch 3 carries a bearing 4 in which is mounted a horizontal winding tube 5. The rear end of this tube traverses the branch 3a of the horizontally extending frame member.

A main driving shaft 7 (Fig. 1) is connected to any suitable, not represented power source.

40 A cam 8 secured to the shaft 7 coacts with a cam follower 9 carried by a lever 10 which is pivotally mounted on a standard 11 supported by the base plate 1 and which is subjected to the action of a spring 9' acting to apply the follower 9 against the cam 8. The lever 10 (Fig. 8) is connected by a link 12 to a slide 13 which is vertically movable along a guide 14 secured to the frame member 2. The slide 13 is provided with a rack 15 which meshes with a pinion 16 mounted on a shaft 17 (Figs. 1 and 2) to which is also secured a gear wheel 18. This latter meshes with a pinion 19 which is mounted on the winding tube 5 by the intermediary of a key 20 (Fig. 9) capable

45 of sliding in a groove 21 extending to the rear end 6 of the winding tube. Thus the pinion 16

communicates a movement of rotation to the tube 5 but is capable of axial movement relatively to the tube 5. The pinion 19 is integral with a sleeve 22 secured to a collar 23; a second sleeve 24 is loosely mounted on the sleeve 22 and has its portion penetrating through the frame member 3 provided with a screw thread on which are screwed a nut 25 and a counter-nut 26 for clamping the sleeve 24 to the frame member 3 and thus holding the pinion 19 stationary in axial direction while the tube 5 is axially movable.

The main driving shaft 7 which is journaled in a standard 27, carries a bevel wheel 28 meshing with a bevel wheel 29 fixed on a shaft 30 which is journaled in standards 31 and 32 (Figs. 1 and 2). The shaft 30 carries a cam wheel 33 coaxing with a cam follower 34 carried by a lever 35 which engages a collar 36 secured to the winding tube 5 by means of a screw 37 (Fig. 9). Rotation imparted to the cam wheel 33 causes oscillation of the lever 35 and accordingly an axial to-and-fro movement of the tube 5. A spring 38 (Fig. 2) holds the cam follower 34 applied against the cam wheel 33.

The front portion of the winding tube 5 extends through a stripping tube 39 (Figs. 9 to 11) which is axially movable independently of the winding tube 5, but which turns together with the winding tube. Axial movement of the stripping tube is effected by means of a cam wheel 40 carried by the shaft 30 (Fig. 1) and coaxing with a cam follower 41 on a lever 42 engaging a collar 43 secured to the stripping tube 39 by means of a screw 44. Rotation of the cam wheel 40 causes an oscillating movement of the lever 42 and a corresponding axial movement of the stripping tube 39. A spring 45 maintains the cam follower 41 applied against the cam wheel 40. The end of the stripping tube is provided with a thread cutting knife 54 the purpose of which will appear later on.

The front end of the winding tube 5 is provided with two radially extending thread carriers 46 (Figs. 9 to 11), and the front end of the stripping tube 39 is provided with a recess 47 permitting axial movement of the stripping tube relative to the winding tube 5 until the front end of the stripping tube arrives at the front end of the winding tube. This latter carries a supporting piece 48 on which is adjustably fixed, by means of screws 49, a clamping spring 50, the front end of which coacts with the front end of the winding pipe for clamping the piece of thread or string used for forming the knot. The supporting piece 48 extends through a slot 51 in the stripping tube 39, for permitting axial movement of the stripping tube relatively to the winding tube. The free end of the spring 50 fits in a notch 52 provided at the front end of the winding tube 5 (Figs. 10 and 11) to ensure a safe clamping of the thread or string. The end of the stripping tube 39 cooperates with the clamping spring 50 in such manner that upon advancing the stripping tube, the end of this tube slightly lifts the spring off the tube 5 in order that the piece of thread 53 can be introduced between the spring end and the tube (Fig. 10).

The thread or string serving for tying the knot is fed from a ball 55 (Figs. 1 and 5) which is disposed in a cup 56 formed on a frame member 57. The thread 58 passes through a thread clamp 59, over a guide fork 60, through a guide 61, a clamp 62 and a guide 63 to be gripped by nippers 64. One of the clamping jaws of these

nippers is provided with a rearwardly directed extension 65 having its end engaged in a guide 66 which is pivotally mounted at 67. The guide 66 is connected by a link 68 to a lever 69 carrying a cam follower 70 which a spring 71 applies against a cam wheel 72 on the shaft 7. Rotation of this cam wheel results in a movement of oscillation of the lever 69 and of the guide 66, which causes opening and closing of the nippers 64 in the desired moment for releasing the gripped end of the thread or for gripping a new length of thread.

The nippers 64 are carried by a slide 215 movable along guides 221 and connected by a rod 216 to a lever 217 carrying a cam follower 218 which is applied by means of a spring 220 against a cam wheel 222 mounted on shaft 7. Rotation of this cam wheel results in a vertical movement of the nippers 64.

When the nippers 64 grip the free end of the thread as shown in dash and dot lines in Fig. 5, a thread feeder pin 73 engages the thread at the right side thereof as shown in dash and dot lines in Fig. 5. This pin 73 is secured to a slide 74 (Fig. 7) movable in a guide 75 which itself is carried by a slide 76 movable along guides 77. The slide 76 is connected by means of a rod 78 to a lever 79 carrying a cam follower 80 applied against a cam wheel 81 on the main driving shaft 30 by means of a spring 82. Rotation of the cam wheel 81 results in an oscillating movement of the lever 79 and accordingly in a movement of the slide 76 along the guides 77. Thus the thread feeder 73 can move from the position shown in dash and dot lines in Fig. 5 to the position shown in full lines in Figs. 5 and 7, and during this movement, while the end of the thread 58 is gripped by the nippers 64, the feeder 73 unwinds a certain length of thread which is folded in two halves so as to form a loop 83.

The slide 74 of the thread feeder 73 is engaged in an oscillatable guide 84 pivotally mounted at 85. At the rear end, not shown in Fig. 7, the guide 84 is engaged by a lever 86 (Fig. 1) pivoted at 87 on the base plate 1 and carrying a cam follower 88 which is applied against the cam wheel 89. Rotation of the cam wheel 89 causes a movement of oscillation of the lever and of the guide 84 which produces a backwards and forwards motion of the slide 74 with the thread feeder 73. The cam wheels 81 and 89 cooperate in such manner that when the slide 76 is in its extreme right hand position as shown in dotted lines in Fig. 5, the slide 74 advances so as to bring the thread feeder against the thread; then the slide 76 moves to its left hand position shown in Fig. 7 and when it arrives there, the slide 74 is retracted to the position shown in dash and dot lines in this figure.

Before such retraction of the thread feeder 73, the looped end 83 of the thread is gripped by nippers 90 (Fig. 2), so as to hold the looped thread in the position in which it had been brought by the thread feeder 73. One of the jaws of the nippers 90 carries an upwardly directed extension 91 which is applied by means of a spring 95 against an abutment roller 92 carried by an arm 93 fast on a frame member 94. The other jaw of the nippers is formed on a lever 96 connected by a rod 97 to a lever 98 carrying a cam follower 99 which is applied against a not represented cam wheel on the shaft 30 by means of a spring 100. Rotation of this cam wheel causes an oscillating movement of the levers 98 and 96 and a corresponding opening

or closing movement of the nippers 90. A movement of the lever 96 in clockwise direction causes gradual opening of the nippers, the jaw extension 91 sliding upwards along the roller 92 which opens the jaw, while movement of the lever 96 in opposite direction causes gradual closure of the nippers.

When the thread feeder 73 is retracted from the thread loop 83, a pair of pliers 101 grip the looped end (Figs. 5 and 10) and pull the thread transversely relatively to the winding tube 5 in front of this tube as represented in Fig. 10. One of the jaws of these pliers 101 is provided with a rearwardly directed extension 102 slidably engaged in a guide lever 103 pivotally mounted at 104 on the frame. The guide 103 is connected by a rod 105 to a lever 106 carrying a cam follower 107 which is applied by a spring 108 against a cam wheel 109. This cam wheel is mounted on a shaft 110 journaled in standards 111 and receiving its movement from the shaft 30 by means of bevel gears 112 (Fig. 1). A movement of rotation of the cam wheel 109 results in an oscillation of the lever 106 and of the guide lever 103 to cause opening and closing of the tongs 101 in the desired moment. These tongs are carried by a slide 113 which is connected by a rod 114 to a lever 115 pivotally mounted at 116 on the frame plate 117. The lever 115 carries a cam follower 118 applied against a cam wheel 119 by a spring 120. Movement of the cam wheel 119 causes oscillation of the lever 115 and a reciprocating movement of the slide 113. Thus when the tongs 101 grip the looped end 83 of the thread, the slide 113 moves towards the left in Fig. 5 and the thread is pulled in front of the winding tube 5 as shown in Fig. 10.

A pair of scissors 121 (Fig. 7) is provided to cut the looped thread to the desired length. The two jaws of the scissors are pivoted on a frame member 122 and the rear end of each jaw is connected by a rod 123 and 124, respectively, (Fig. 1) to a lever 125 pivoted on an axis 126 to which is secured a link 127 connected to a rod 128. This rod is connected to a lever 129 pivoted at 130 on a standard 131 and carrying a cam follower 132 which is applied against a cam wheel 133 by a spring 134. Upon rotation of the cam wheel 133, the lever 125 executes a movement of oscillation which causes the scissors to close and to open for cutting the desired length of thread from the unwinding thread 58.

When the cut off piece of thread 53 (Fig. 10) has been moved in front of the winding tube 5 by the tongs 101 and is held tensioned by the friction of the nippers 90, the stripping tube 39 is moved forward relatively to the winding tube and lifts the clamping spring 50 off the winding tube. Both tubes 5 and 39 are then slightly moved forwards so that the thread is engaged between the spring 50 and the tube 5, and after retraction of the stripping tube 39, the thread is tightly gripped between the spring and the tube 5. The tongs 101 now abandon the looped end of the thread and the winding tube 5 starts to turn owing to the action of the cam 8 and the rack 15. The tube 5 thus makes about two and one half revolutions. Simultaneously the tube 5 is axially moved owing to the action of the lever 35 and the cam 33. Owing to the movement of rotation of the tube 5, the thread is wound around the tube and the guide nippers 90 hold the thread with such friction, that the thread is laid close about the tube and the thread carriers 46. During about the first half revolution of the

tube 5, this latter is pulled slightly backwards and afterwards it is moved forwards; accordingly, the first winding 135 of the thread is laid around the tube 5 (Fig. 11), and owing to further axial displacement the second winding 136 extends backwards and passes over the first winding 135 and over the thread carriers 46 which are provided with recesses 137 for retaining the thread. Now the tube 5 is again axially retracted for a slight amount, so that the third winding 138 passes over the second winding 136 and over steps 139 of the thread carriers, these steps having a smaller radial distance from the tube 5 than the recesses 137. The looped end 83 of the thread now penetrates from between the second and third winding.

Above the winding tube 5 there is disposed a hook or needle 140 (Figs. 2, 5 and 11) which can move up and down, and forwards and backwards. This hook is attached to a slide 141 movable along guides 142 which are carried by a vertically movable slide 143 moving in guides 144. The slide 141 is connected by a rod 145 to a lever 146 carrying a cam follower 147 which is applied by means of a spring 148 against a cam wheel 149. Rotation of this wheel causes an oscillating movement of the lever 146 and accordingly a horizontal reciprocating movement of the hook 140. The vertical slide 143 is connected by a rod 150 to a lever 151 carrying a cam follower 152 and applied against a cam wheel 153 by a spring 154. Rotation of this cam wheel results in a vertical movement of the hook 140. In Fig. 2 the hook is represented in raised position. After the piece of thread has been wound around the winding tube 5, the hook is lowered and then pushed forwards and slightly raised again. In this manner, the hook is advanced between the two thread carriers 46 (Fig. 11) and engages the third winding 138 of the thread. Now the hook is moved backwards and pulls the winding 138 underneath and past the second winding 136, whereby the free end of the thread is pulled out of the nippers 90; afterwards the hook with the engaged thread is raised again to the position shown in Figure 2. The thread wound about the tube 5 now possesses the required shape for forming a knot, as represented in Fig. 12. It is now only necessary to grip the two ends of the wound up thread, to strip the windings off the winding tube on the article to be tied, and to pull the knot tight.

Two pairs of gripping tongs 155 and 156, one above and one below the winding tube 5, are provided for gripping the two ends of the thread wound on the winding tube, and for pulling the knot tight (Figs. 3 and 12). One of the jaws of the tongs 155 is provided with a downwardly directed extension 157 engaging a guide lever 158 pivotally mounted at 159. The tongs 155 themselves are carried by a slide 160 which is vertically movable in guides 161 and which is connected by means of a rod 162 to a lever 163 carrying a cam follower 164 which is applied against a cam wheel 165 by a spring 166. The guide 158 is connected by a link 167 to a lever 168 carrying a cam follower 169 which is applied against a cam wheel 170 by means of a spring 171. The lever 163 is pivotally mounted at 172 on a standard 173, while the lever 168 is pivotally mounted at 174 on the base plate 1. The cam wheels 165 and 170 are mounted on the shaft 110. It is understood that rotation of these two wheels causes a movement of oscillation of the two levers 163 and 168 and accordingly in an opening and

closing movement of the jaws of the tongs 155 combined with a vertical reciprocating movement of the tongs, so that these latter grip the looped end of the thread wound on the tube 5 and may pull the knot tight after it had been stripped from the winding tube and pushed on the article to be tied.

One of the jaws of the upper gripping tongs 156 is provided with an extension 175 engaging a guide lever 176 which is pivotally mounted at 177 on the frame. The tongs themselves are carried by a slide 178 movable in guides 179 and connected by a link 180 to a rod 181 (Figs. 1 and 2) which is vertically movable in guides 182 and connected by a link 183 to a lever 184 pivotally mounted at 185 on a standard 186 and carrying a cam follower 187 which is applied against a cam wheel 188 by the action of a spring 189. The guide lever 176 cooperates with a push rod 190 having an inclined end face 191 (Figs. 2 and 4). The rod 190 is guided in a fixed bracket 192 and urged against the guide lever 176 by means of a spring 193. The rod 190 is connected to a lever 194 carrying a cam follower 195 which is applied against a cam wheel 196. The spring 193 tends to urge the rod 190 against the guide 176 whereby the inclined surface 191 produces a movement of oscillation of the guide 176 in clockwise direction in Fig. 3 resulting in an opening of the tongs 156, while the cam wheel 196 acts against the spring 193 and withdraws the push rod 190 from engagement with the guide 176, permitting the spring 197 to move the guide in counterclockwise direction to close the tongs 156.

The articles 198 to be tied by the knot made with the described machine are represented as having sausage shape and being wrapped in any kind of wrapping material which is to be tied. These articles are brought in any known manner in wrapped condition on a feeding plate 199 to the place of operation in front of the winding tube 5, where they are in axial alignment with the winding tube. A holding member 200 is destined to maintain each article in place while the knot wound on the winding tube 5 is being pushed over the end of the wrapping material and pulled tight by the tongs 155 and 156. The holding member 200 is carried by a slide 201 movable in guides 202. A spring 203 urges the holding member downwardly against the article so as to provide a yielding pressure, and an abutment nut 204 is provided to limit and adjust the movement of the holding member. A bolt 205 penetrating through a slot 206 in the guide 202 connects the slide 201 to one end of a lever 207 pivotally mounted at 208 and having its other end connected to a rod 209 which itself is connected to a lever 210 carrying a cam follower 211 coacting with a cam wheel 212 on the shaft 30 (Fig. 1).

When an article 198 arrives opposite the free end of the winding tube 5, as shown in Figure 2, the knot has been wound on the tube and the two ends of the knot are being gripped by the tongs 155 and 156; this is the position shown in Fig. 12. The winding tube 5 and the stripping tube 39 are now advanced towards the article 198 so that the tube 5 passes over the shrunk end of the wrapping material. Then the stripping tube 39 alone advances and lifts the clamping spring 50 off the winding tube to release the clamped end of the wound up thread while simultaneously stripping the thread from the winding tube to place it on the shrunk end of the wrapping material as represented in Fig. 13. The two tongs 155 and 156 are now moved outwardly

relatively to the article by corresponding movement of the controlling cam wheels 165 and 188 and pull the knot tight. Then the two tubes 5 and 39 are rotated together in the direction of the arrow *f* in Fig. 10, so that the forwardly projecting knife 54 cuts the free end 212 (Fig. 13) of the thread. The looped end 33 is not cut and can serve to suspend the article. The holding member 200 is now lifted again from the article and this latter being released, can move further along the feedway 199 to fall in a not represented receiving box or the like. Untying of the knot made as described, by a pulling action on one of the ends of the thread, is not possible.

For tying the other end of the articles 198 of sausage shape, these latter can be brought on the feedway in reversed position. However, it is also possible to provide a winding device on either side of the feedway so that the article can be simultaneously tied at both ends. Such a machine is diagrammatically represented in Fig. 15. The feedway 199 carrying articles 198 is disposed in the center of the machine. At the place of operation, the article is held by a holding member 200 similar to that described with reference to Fig. 6. At either side of the article there is disposed a winding device similar to that described and comprising each a winding tube 5 and a stripping tube 39. There are two shafts 30 each carrying the series of cams necessary for the operation of one of the winding devices, while a single shaft 110 is sufficient for carrying the two pairs of cams required for the operation of the lower knot tightening tongs.

Since the article needs to be suspended with one of its ends only, a loop 15 must be provided at one side only of the article. Accordingly a double thread for forming the knot is required at one side only, while on the other side a simple thread will be used for making the knot, which otherwise is made in the same manner as the described knot with the double thread.

Although there is illustrated a particular embodiment of our improved knot tying machine, we do not desire our invention to be limited to the particular arrangements disclosed, and it is to be understood that various modifications in construction, form and arrangement of parts may be made without departing from the scope of the appended claims.

We claim:

1. A machine for tying knots of string or the like, comprising a winding device having a rotatable winding member arranged for axial movement, means for clamping a piece of knot material thereto, means for imparting at least two revolutions to the winding member to place the knot material in at least two windings about the latter, means for axially moving the winding member to-and-fro during its movement of rotation, and a stripping member for stripping the wound knot from the winding member and sliding it upon an article.

2. A machine as claimed in claim 1, wherein the winding member forms a cylindrical body which, at one end, is provided with a clamping spring for holding the knot material, and which carries at least one radially directed string carrier in such manner that during rotation and axial movement of the winding member one winding is placed around the cylindrical surface of the winding member and another winding over the string carrier.

3. A machine as claimed in claim 1, and com-

prising a string carrier provided with two supporting faces for the knot material disposed at different radial distances from the axis of the winding member, the winding member being turned and displaced in such manner that one winding of the knot material is placed around the cylindrical face of the winding member, a second winding around the supporting surface having the greater radial distance, and a third winding around the supporting surface with 10 smaller radial distance.

4. A machine as claimed in claim 1, wherein two gripping tongs are arranged to move in a plane which is perpendicular to the axis of the winding member, and are destined to grip the 15 two ends of the wound knot and to pull the same tight.

5. A machine as claimed in claim 1, characterised in that a feeding way for feeding the articles to the winding device is provided opposite 20 the end of the winding member, each article being maintained at the place of operation by a pressing plate.

6. A machine as claimed in claim 1, and comprising a feeding way and a winding device disposed on either side of the feeding way.

7. In a method of forming knots from string or like flexible material, the steps which comprise folding a piece of knot material in two halves to form a double length of knot material having a loop at one end thereof, clamping the looped end of knot material, winding the double length of knot material on a winding member to form a loose knot thereon, stripping the loose knot from the winding member, transferring the knot to an article to be tied, and then pulling the knot tight, whereby said article may be suspended on the looped end of the knot material.

8. In a method of forming knots from string or like flexible materials, the steps which comprise folding a piece of knot material in two halves to form a double length of knot material having a loop at one end thereof, clamping the looped end of the knot material to a winding member, winding the double length of knot material about the winding member in relatively staggered and superposed windings to form a loose knot thereon, bringing an article to be tied in position to receive the loose knot, stripping the loose knot from the winding member, transferring the loose knot on said article, and then pulling the knot tight, whereby said article may be suspended on the looped end of the knot material.

9. In a method of tying up articles which are to be suspended, the steps which comprise folding a piece of string in two halves to form a double length of string having a loop at one end thereof, clamping the looped end of the string to a winding member, winding the double length of string in two relatively staggered and superposed windings about the member, passing the free end of the double string underneath the first winding to form a loose knot on the winding member, bringing an article to be tied in position to receive the loose knot, stripping the loose knot from the winding member, transferring the loose knot on the article, and then pulling the knot tight, whereby said article may be suspended on the looped end of the string forming the knot.

10. A machine for tying knots of string or like

material, comprising a winding device having a rotatable winding member arranged for axial movement, means for clamping one end of a piece of knot material thereto, means for imparting at least two revolutions to the winding member to place the knot material in substantially two windings about the winding member, means for axially moving the winding member to-and-fro during its movement of rotation, a movable hook-shaped member for engaging the free end of the knot material and passing said end underneath one of the windings on the winding member to form a loose knot on said member, and a stripping member for stripping the loose knot from the winding member and transferring it upon an article.

11. A machine for tying knots of string or like flexible material, comprising a winding device having a rotatable winding member arranged for axial movement, a clamping spring carried by said winding member for clamping one end of a piece of knot material thereto, means for imparting a movement of rotation to the winding member to place the knot material in substantially two windings about the winding member, means for engaging the free end of the knot material wound on the winding member and passing this end underneath one of the windings on the winding member to form a loose knot thereon, an axially movable stripping pipe surrounding the winding member, means of moving the stripping pipe to the end of the winding member to strip the wound knot off the winding member and transferring it upon an article, the stripping pipe cooperating with said clamping spring upon being moved to the end of the winding member to lift the spring and release the clamped end of the knot material.

12. A machine for tying a knot of string or like flexible material about an article, comprising a winding device having a hollow rotatable winding member arranged for axial movement, means for feeding a piece of knot material transversely in front of the winding member, a clamping spring carried by said winding member, means for axially moving said winding member towards said transversely fed piece of knot material to have one end of the knot material engaged by said clamping spring, means for rotating the winding member to place the knot material in substantially two windings about the winding member, means for engaging the free end of the knot material wound on the winding member and for passing said end underneath one of the windings on the winding member to form a loose knot on this member, an axially movable stripping pipe surrounding the winding member, means for bringing an article in front of the hollow winding member, means for advancing the hollow winding member over one end of said article, means for moving said stripping pipe to the end of the winding member to strip the wound knot off the winding member and transferring it upon the article, said stripping pipe cooperating with said clamping spring upon being axially moved to the end of the winding member to lift the spring and release the clamped end of the knot material, and means for pulling the loose knot tight on said article.
